UNITED STATES PATENT OFFICE.

ALBERT L. PLATT, OF CLINTON, ILLINOIS.

AERIAL TOP.

No. 813,519.

Specification of Letters Patent.

Patented Feb. 27, 1906.

Application filed June 20, 1905. Serial No. 266,131.

To all whom it may concern:

Be it known that I, ALBERT L. PLATT, a citizen of the United States of America, residing at Clinton, in the county of DeWitt and State of Illinois, have invented certain new and useful Improvements in Aerial Tops, of which the following is a specification.

This invention relates to toys belonging to the class of buzzers and whirligigs, and has special reference to a simple and practical construction of aerial top.

To this end the invention has in view an aerial top so constructed as to be easily and quickly manipulated, while at the same time embodying means for imparting a rapid spinning motion to the whirling member by a single spiral wrap of the cord about the spinning-stem of said member.

With these and other objects in view, which will more readily appear as the nature of the invention is better understood, the same consists in the novel construction, combination, and arrangement of parts, which will be hereinafter more fully illustrated, described, and claimed.

The essential feature of the invention involved in the manner of housing and guiding the operating-cord is necessarily susceptible to some structural change without departing from the scope of the invention; but a preferred embodiment thereof is shown in the accompanying drawings, in which—

Figure 1 is a perspective view of a top embodying the present invention, showing the whirling member carried by the supporting-handle in a position to be operated. Fig. 2 is a longitudinal sectional view of the top, showing the arrangement of the operating-cord for spinning and projecting the whirling member. Fig. 3 is a detail view of the whirling member as it appears while in flight.

Like reference-numerals designate corresponding parts in the several figures of the drawings.

The toy in its general organization essentially comprises a supporting member 1; a whirling member 2, and an operating-cord 3. The supporting member of the toy is preferably in the form of a tubular handle providing a holder which can be conveniently and readily grasped by one hand of the operator, thus leaving the other hand free for manipulating the cord to provide for whirling and projecting the whirling member or top proper.

The longitudinal bore 4 of the said support-

ing-handle extends throughout the entire length of the latter and constitutes a guiding means for the spinning-stem 5 of the whirling member 2, whereby the latter is projected from the supporting-handle in a substantially straight line. The said whirling member 2 essentially consists of the spinning-stem 5 and the screw-propeller blade 6, secured fast upon one end of the stem and disposed at right angles to the axis thereof. The propeller-blade 6 is formed with the opposite reversely-inclined wings 7, which provide the conventional screw-propeller action when a whirling motion is imparted to the whirling member or top proper and which action serves to maintain the whirling member in flight as long as the speed of rotation is sufficient.

A distinctive feature of the invention resides in the novel manner of housing and guiding the operating-cord 3. This cord is threaded through a cord-holding guide-eye 8, piercing the wall of the tubular handle 1 near the upper end of the latter, and is designed to be drawn or pulled through a drawing-kerf 9, formed in the top edge of the handle in a higher plane than the eye 8. The said kerf 9 is formed with a downwardly-sloping base 10 to form a guiding-surface over which the operating-cord may be freely drawn, and in the interval between the guide-eye 8 and the kerf 9 the cord 3 is designed to be given a single spiral twist 3^a about the stem 2 of the whirling member. By reason of this single spiral twist of the operating-cord the latter may be quickly drawn from the eye 8 through the kerf 9 to impart a rapid-spinning motion to the stem 2 and the propeller carried thereby, while at the same time serving to mechanically lift the stem 5 out of its guiding-bore 4 and forcibly project the whirling member or top proper into the air.

In operating the toy it is simply necessary to drop the stem 5 in the supporting-handle, place a single twist of the cord about the said stem, and drop the pull end thereof into the kerf 9. It is then simply necessary to draw out the cord rapidly through the kerf to secure the action referred to.

To provide proper and free play for the spiral wrap of the operating-cord, the supporting-handle 1 is formed in its upper end with an enlarged housing-socket 11, which is an enlargement of the guiding-bore.

Having thus described the invention, what

is claimed, and desired to be secured by Letters Patent, is—

An aerial top, comprising a tubular supporting-handle provided near its upper end 5 with a transversely-disposed cord-holding guide-eye, and in its top edge in a higher plane than the eye with a downwardly-sloping drawing-kerf, said handle being also provided at its top edge with an enlarged housing-socket, a whirling member consisting of a spinning-stem lying within the bore of the supporting-handle, and a propeller-blade car-

ried by said stem, and an operating-cord passing through the guide-eye and drawing-kerf and having its portion between these elements arranged about said stem in a single spiral wrap, the latter being arranged to operate in said housing-socket. 15

In testimony whereof I affix my signature in presence of two witnesses.

ALBERT L. PLATT.
